US00D959470S

(12) **United States Design Patent** (10) Patent No.: **US D959,470 S**
 (45) Date of Patent: **** Aug. 2, 2022**

(54) **DISPLAY SCREEN OR PORTION THEREOF WITH GRAPHICAL USER INTERFACE**

(71) Applicant: **Lutron Technology Company LLC**,
 Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Shenchi Tian**, Easton, PA (US)

(73) Assignee: **Lutron Technology Company LLC**,
 Coopersburg, PA (US)

(**) Term: **15 Years**

(21) Appl. No.: **29/780,927**

(22) Filed: **Apr. 27, 2021**

Related U.S. Application Data

(63) Continuation of application No. 29/707,327, filed on Sep. 27, 2019, now Pat. No. Des. 920,360, which is a continuation of application No. 29/663,983, filed on Sep. 20, 2018, now Pat. No. Des. 866,588, which is a continuation of application No. 29/607,668, filed on Jun. 15, 2017, now Pat. No. Des. 830,409.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design. The interior broken lines illustrate portions of the graphical user interface which form no part of the claimed design.
